UNITED STATES PATENT OFFICE.

ELIE AMOUROUX, OF PARIS, FRANCE, ASSIGNOR TO ALFRED LA ROCHE AND ANTOINE JULIEN CHAMPION, BOTH OF SAME PLACE.

FEED-WATER ALARM FOR STEAM-BOILERS.

SPECIFICATION forming part of Letters Patent No. 338,015, dated March 16, 1886.

Application filed January 16, 1886. Serial No. 188,727. (No model.)

To all whom it may concern:

Be it known that I, ELIE AMOUROUX, of the city of Paris, France, have invented a new and Improved Feed-Water Alarm for Steam-Boilers, of which the following is a full, clear, and exact description.

All those connected with steam-engines are aware of the great value of an alarm-whistle for preventing explosions in steam-boilers; 10 but owing to the various improvements in boilers and the exigencies of their construction it has been found impossible in many cases to provide them with a float, upon which, as is well known, the action of the alarm depends, 15 and from this cause a great number of boilers are deprived of such a safeguard and are entirely dependent for their safety upon the vigilance of the stoker or driver, and are always a source of possible danger both to life and 20 property in their vicinity.

The object of the present invention is to provide a boiler-alarm which, although based on the same physical principles as heretofore, shall be arranged entirely outside the boiler 25 without any internal fittings, and which may, moreover, be placed at a distance from the said boiler at any part of the works, or even at several points, if desired.

The apparatus, which is of very simple construction, is illustrated in the accompanying drawings, wherein Figure 1 represents a longitudinal elevation, and Fig. 2 a transverse section of the same on line A B of Fig. 1. Fig. 3 is a vertical cross-section of part of the apparatus, showing a modification. Fig. 3^{1/2} is a 30 horizontal section of the curtain Z, which is shown in Fig. 3.

R is a small container placed at the low-water level X—that is to say, at a level below 40 which the water in the boiler would not fall without causing an explosion—and connected to boiler C in the same manner as a water-gage—that is to say, by means of two tubes, T T', in the same vertical plane and in constant 45 communication the one with the steam and the other with the water. In this case, however, the tubes, instead of being rigid like those of a water-gage, are made flexible by giving them a spiral form, as shown at H, or in other manner, for the purpose of enabling the container 50

R to rise and fall without the necessity of having jointed connections. It is upon this principle of elasticity of its connections and the difference in weight of the water in the container consequent on the variations in the 55 level of the water in the boiler that the apparatus is based. The container R is also attached to the end of a lever, L, in the same manner as the weight of a safety-valve, to which, moreover, it bears an exact resemblance and acts in identically the same manner, as will be seen hereinafter. This lever is caused by a suitable arrangement to act on the valve of the steam-whistle, so as to hold the 60 same closed when the container R is of initial 65 weight—that is to say, so long as the water it contains remains at the same level—and allows said valve to fully open immediately the level falls—that is to say, when the weight of the container is reduced.

As will be seen, the apparatus acts both as a water-gage and a safety-valve, consisting simply of a valve loaded by the weight of the water in a container placed, as before mentioned, at the low-water level X. Thus, if the 75 water in the boiler should fall below this point, as the container is in constant communication therewith, the water which it contains will pass out to a corresponding extent, and the weight will gradually fall, thus allowing the 80 valve to open and steam to escape and sound the whistle.

In order to render the action more certain, the arm P, Fig. 2, is extended at Q beyond the fulcrum X², upon which is mounted an adjustable weight, V. The position of this weight is adjusted, when the water is at its lowest level and steam is up, by sliding the weight on the arm until the steam-pressure opens the valve. As soon as the feed is started, the water rises in the container R at the same time as in the boiler, and the weight of the water in the container closes the valve, which is the 85 normal position of the apparatus.

In marine-boilers, where the water-level is 95 liable to be affected by the rolling and pitching of the vessel, it is preferred, in order not to affect the proper working of the apparatus, to cover the water-inlet orifice of pipe T' from the boiler with two perforated caps, S S', (see 100

Fig. 2,) which retard the inflow and out-flow of the water. I may also with the same object employ the arrangement represented in Fig. 3, which consists in simply covering the water-inlet to the tube T' with a curtain or cap, Z, whereby the fluctuations at the surface of the water will not affect the water contained within said curtain, and prevent any sudden inflow or outflow of water. The curtain or cap T' is open at both ends and semicircular in cross-section, as shown in Fig. 3bis; but the cross section may be of any other convenient form.

The apparatus represented in the drawings is given merely by way of example, as it will be understood that the form and dimensions may be varied to suit the particular circumstances of each case.

I do not claim a swinging vessel having a

pivotal connection such as is shown in Pat- 20 ent No. 237,929.

I claim—

A feed-water-alarm apparatus for steam-boilers, consisting in the combination of a container, R, with the two flexible tubes T T', 25 having spiral parts H H', which allow of said container rising and falling, and with the lever L, yoke M, and lever P Q, and weight V, all arranged to operate by the vertical movement of the container R, as set forth. 30

The foregoing specification of my improved feed-water alarm for steam-boilers signed by me this 30th day of December, 1885.

ELIE AMOUROUX.
